UNITED STATES PATENT OFFICE.

WILLIAM J. REILLY, OF DENVER, COLORADO.

SUSPENDED FURNACE-ROOF.

1,173,862.

Specification of Letters Patent. Patented Feb. 29, 1916.

Application filed November 9, 1914. Serial No. 871,034.

To all whom it may concern:

Be it known that I, WILLIAM J. REILLY, a citizen of the United States, residing in the city and county of Denver and State of Colorado, have invented certain new and useful Improvements in Suspended Furnace-Roofs; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to improvements in suspended furnace roofs, my object being to overcome the difficulties heretofore experienced in roofs of this general type. Some of these difficulties will now be enumerated.

20 Heretofore, the refractory bricks have been so held in place as to cause them to bind upon themselves, and to crimp the suspending iron frame; thus leaving no adjacent room between bricks or iron work 25 which would allow for expansion of the materials composing the roof at a time when the furnace is operating. As a consequence of this rigidity of suspension, the bricks spall off at their working faces. This spalling continues until the suspending iron

30 frame is finally exposed to the direct heat of the furnace, thus resulting in its distortion, and the failure of the roof as a whole, if the furnace is not taken out of service.

35 In constructions of this character, it is impossible to remove an individual brick while the furnace is working, in fact, the time when a furnace having this form of roof is ready for service, is when the roof is intact. 40 The failure of any one brick in the structure requires a shutting down.

In my improved construction, the supporting frame member is removed from the destructive heat of the furnace, both when 45 the furnace roof is intact and when a brick has dropped out; by reason of the distance, the under side of the suspending member is removed from the heat of the furnace.

My improved suspension means consists 50 of a series of individual members located as required, each being distinct and separate from its adjacent similar member, and each brick is individually suspended in its required vertical position, and is free to 55 move in any direction in response to the changes in temperature. Again, each brick

is individually removable and replaceable, while the furnace is working under heat, as well as when it is out of service. In fact, the whole brick roof structure is free to 60 move as a unit in any horizontal or vertical direction, because of the clearance space provided in the side and end walls of the furnace, which space is filled with an elastic, compressible and non-combustible material. 65

The materials under treatment in a hot furnace,—when this furnace is provided with an arch roof, are not uniformly heat-treated, because of the varying distance of the face of the arch roof from the materials 70 under treatment, the greatest distance being under the crown of the arch. In my improvement, the face of the roof or its under surface is transversely parallel with the bed or floor of the furnace, but it may, if desired, have a variable distance from the furnace bed in a longitudinal direction, whereby a uniform distance across the furnace is maintained, and whereby, if desired, a progressively increasing distance of the face of 80 the roof from the furnace bed is available. This increasing distance is at times advantageous because of the heating of the gases as they move forwardly, resulting in their requiring more space and freedom of movement. 85

In my improved construction, each brick is to be provided where required, with a relatively small opening, beginning at the under side of the suspending member within 90 the brick, and extending down to the working face of the brick. The intention of this is to provide a means of introducing into the furnace and under the roof where it is needed, streams of oxygen or other necessary gases. It may not be necessary to have each brick so perforated. In any event, the perforated bricks may be of such number and so positioned with reference to the object to be attained as to efficiently perform 95 100 the required function.

Having briefly outlined my improvement, I will proceed to describe the same in detail, reference being made to the accompanying drawing, in which is illustrated an embodiment thereof. 105

In this drawing,—Figure 1 is a transverse sectional view of a furnace equipped with my improved suspended roof. Fig. 2 is a section taken on the line 2—2, Fig. 1, looking toward the left. Fig. 3 is a perspective detail view of one of the bricks of which the 110

roof is composed. Fig. 4 is an end elevation of one of the bricks with the suspension device attached. Fig. 5 is a view of the same taken at right angles to Fig. 4, or looking in 5 the direction of arrow 5. Fig. 6 is a perspective view of one of the brick suspension devices, or hangers.

The same reference characters indicate the same parts in all the views.

- 10 Let the numeral 5 designate the fire box of a furnace; 6 the grate and 7 the side walls. Mounted in these side walls and extending transversely across the furnace at a suitable distance above the grate, is a number 15 of suspension bars 8, which, as illustrated in the drawing, have the shape of an inverted T. To each of these bars is connected a pair of hangers 9, each hanger having a projection 10 at its upper extremity 20 adapted to enter an opening 12 formed in the bar 8, each opening 12 as disclosed in the drawing, being of sufficient size to receive the projections 10 of two of the hangers 9, the said projections extending at right angles 25 to the body 13 of the hanger. To the lower extremity of each of these hangers is connected a brick 14, constituting a part of the roof of the furnace which is composed of a number of rows of these bricks extending 30 both transversely and longitudinally of the furnace. A number of bricks 14 is suspended from each bar 8, and, consequently, the bricks suspended from a single bar constitute a row of bricks extending trans- 35 versely of the furnace.

As illustrated in the drawing, the two outermost bricks 14 of each transverse row, have portions 15 of their lower surfaces in engagement with shoulders or offsets 16 40 formed in the wall of the furnace. Each of these shoulders extends beyond the engaging face of the brick, as shown at 17, and between the brick and the vertical face 18 of the side wall is located a filling 19 of some 45 suitable elastic or compressible non-combustible material, as asbestos, which will allow or compensate for expansion in a transverse direction, of the entire transverse row or series of bricks suspended from a single 50 bar 8. Furthermore, the bricks are slightly spaced as shown at 20, in order to allow for expansion without unduly compressing the adjacent bricks. In other words, my improved roof is so constructed that ample al- 55 lowance is made for expansion and contraction without in any way injuring the structure from these causes. However, when any brick becomes worn or when, for any reason, it becomes necessary to remove it and substi- 60 tute a new brick, the construction is such that this may be readily accomplished, as hereinafter explained.

The upper portion of each brick is provided with an opening 21 adapted to receive 65 the lower extremity of the hanger 9, which

is perforated as shown at 22, to receive a locking pin 23, which is inserted in the perforation of the hanger by introducing it into one of the open extremities of a transverse perforation 24 which intersects the vertical 70 perforation 21.

In order to make it practicable to easily disengage any brick from the roof of the furnace, without shutting down the furnace or reducing the heat, I prefer to construct 75 the perforation 21 of such shape that it gradually increases in size from its lower extremity upwardly, thus making it practicable to move the upper extremity 10 of any hanger, laterally a sufficient distance to 80 disengage it from the opening 12 of its bar 8, such movement being in a forward or rearward direction, and at right angles to the direction of the locking pin 23, which permits freedom of movement of the hanger 85 in the direction stated, as the pin fits loosely in the perforation 24.

As illustrated in the drawing, the two hangers whose upper extremities 10 enter an 90 opening 12 of the bar, are inserted in the same from opposite sides, the projection 10 extending at right angles to the body of the hanger, and being of sufficient length for the purpose.

As shown in the drawing, (see Figs. 1 and 2), the furnace has a width equal to the aggregate width of six of the bricks 14, while the roof has a depth from front to rear equal to the aggregate thickness of eight bricks, the rearmost brick of each longitudinal row or series resting upon a shoulder 100 25 formed on the front wall of the furnace, the said shoulder being of sufficient length to permit the introduction of a quantity of elastic or compressible non-combustible material 26, as asbestos, the construction in this regard being the same as that heretofore described when referring to material 19 located between the side bricks and the adjacent wall. It must be understood, however, that the area of the roof may be of any suitable or desired dimensions, depending 110 upon the required capacity of the furnace.

As shown in the drawing, every other brick of each transverse and longitudinally disposed row is provided with a relatively small perforation 27 extending from the transverse opening 24 downwardly to the lower face of the brick. The object of these perforations is to make it practicable to introduce into the furnace below the roof, streams of oxygen or other necessary gases, which may be advantageous for the purpose of facilitating combustion, or the general efficiency of the furnace from a standpoint of perfect combustion. This gas may be introduced into the upper compartment 28 of the furnace above my improved roof, and from this compartment, the oxygen or gases of any kind may be caused to pass down- 120 125 130

wardly through the vertical openings 21, across transverse openings 24 and thence downwardly through the relatively small perforations 27 into the combustion compartment of the furnace.

From the foregoing description, it will be understood that when any brick forming an element of my improved roof has become worn or sufficiently injured from any cause, to make it desirable to replace it and substitute another therefor, this may be easily accomplished, since it will be practicable for the person repairing the furnace to enter the compartment 28 above the roof, and work with comparative comfort during the operation of removing one or more bricks and substituting others therefor, even when the furnace is under heat.

From the foregoing description, it will be understood that the individual bricks of the furnace roof are independently mounted and removable independently of each other in an upward direction. In other words, the said bricks are liftably removable independently of each other. Hence, the arrangement of the bars 8 with reference to distance above the bricks and spacing from each other must be such as to permit the bricks to be lifted upwardly from the body of the roof and then raised above the bars 8 by passing between the same. This will necessitate a construction and arrangement which will harmonize with this feature, since by virtue thereof, it becomes practicable to remove one or more bricks while the furnace is under heat and substitute another or others therefor, without shutting down the furnace or reducing its temperature. This is an exceedingly important feature in constructions of this character.

Having thus described my invention, what I claim is,—

1. A furnace roof composed of bricks spaced from each other to permit expansion, suspension means for the bricks consisting of stationary bars, and hangers forming supports for the respective bricks, the hangers being detachably connected with the said bars, and the space between the latter being greater than the width of a single brick whereby each brick may be independently lifted upwardly between the said bars.

2. A furnace roof composed of a series of individual bricks, and means for suspending the said bricks comprising bars extending transversely of the furnace and supported by the side walls thereof, and hangers whose

lower extremities are loosely connected with the bricks and whose upper extremities are bent to enter openings formed in the bars, the hangers of any two adjacent bricks being connected with the same bar and having their upper extremities arranged to pass through the openings in opposite directions, substantially as described.

3. A furnace roof composed of bricks and suspension means therefor, the said bricks each having communicating openings, one of which is vertically disposed while the other is transversely disposed, the vertically disposed opening increasing in size from its lower extremity, the suspension means being composed of stationary bars suitably spaced and provided with openings, and hangers whose lower extremities loosely engage the openings in the respective bricks, while their upper extremities loosely engage the openings in the stationary bars, to permit the independent removal of the individual bricks in an upward direction, substantially as described.

4. A furnace roof composed of a series of individual bricks, each brick having a vertically disposed opening increasing in size from its lower extremity, and a transversely disposed opening communicating with the vertically disposed opening, and hangers for the individual bricks, the lower portion of each hanger entering the vertical opening of one of the bricks, and provided with a perforation, and a locking pin inserted in the transverse opening of the brick and entering the perforation in the lower extremity of the hanger, and stationary bars with which the upper extremities of the hangers are detachably connected to permit independent removal of the individual bricks in an upward direction, substantially as described.

5. A furnace roof composed of bricks spaced from each other to permit expansion, suspension means for the bricks consisting of stationary bars having perforations therein, and hangers forming supports for the respective bricks, the hangers being arranged in pairs and the upper extremities of each pair adapted to be inserted in a single perforation for the purpose set forth.

In testimony whereof I affix my signature in presence of two witnesses.

WILLIAM J. REILLY.
